(57) **CLAIM**

The ornamental design for a surgical simulator device, as shown and described.

DESCRIPTION

FIG. 1 is a perspective view of a simulator device, according to our design;

FIG. 2 is a left side view of the surgical simulator device of FIG. 1;

FIG. 3 is a right side view of the surgical simulator device of FIG. 1;

FIG. 4 is a back view of the surgical simulator device of FIG. 1;

FIG. 5 is a front view of the surgical simulator device of FIG. 1;

FIG. 6 is a top view of the simulator device of FIG. 1; and, FIG. 7 is a bottom view of the simulator device.

The broken lines shown in the figures are included for the purpose of illustrating portions of the surgical simulator device and form no part of the claimed design.
